The ornamental design for an attachment for handheld device, as shown and described.

DESCRIPTION

FIG. 1 is a top, left, front perspective view of an attachment for handheld device according to our new design;

FIG. 2 is a top, right, rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate unclaimed portions of the attachment for handheld device and form no part of the claimed design.

In a preferred embodiment, the nature of this product is an attachment for a handheld electronic device in the form of a housing cover panel or portion thereof.
